UNITED STATES PATENT OFFICE

MAX LUBICH, OF EBERSBACH, GERMANY, ASSIGNOR TO THE FIRM L. SCHULER A.-G., OF GOPPINGEN, WURTTEMBERG, GERMANY

ADJUSTABLE ECCENTRIC

Application filed October 23, 1929, Serial No. 401,804, and in Germany February 19, 1929.

My invention relates to adjustable eccentrics as described in my Patent No. 1,733,162. It is an object of my invention to improve the means described in the said patent, particularly with a view to rendering it suitable for eccentric presses having a plurality of uprights.

The means described in my said patent comprises a key which is inserted at one side of the clutch member which is adapted to be shifted. This one-sidedness may cause jamming. In a press having a single upright only the member is freely accessible from the front end of the shaft so that it can readily be handled in case of jamming but in a press having a plurality of uprights such handling would be interfered with by one of the uprights. Therefore, I so design my novel means that it is not subject to jamming.

To this end, instead of a single one-sided key, I provide two keys arranged diametrically opposite each other in the coupling member and connect the two keys by a pin which extends eccentrically to the axis of the two keys and is connected with the shaft by means of a guide extending at right angles to the axis of the shaft, the guide being so designed as to effect a positive connection of the shaft and the clutch member in axial direction but providing a clearance for the pin at right angles to the axis, so as not to interfere with its rotation.

By these means the one-sided key according to my said patent is duplicated, one-sided action and jamming are eliminated, and handling of the coupling member is not required.

My novel arrangement involves the further advantage that it is more simple and more readily surveyed than my said prior means, and in particular the spring-controlled shifting member of the prior device is eliminated.

Suitable means, for instance, a set screw, are preferably provided for holding the two keys in position.

In the drawings affixed to this specification and forming part thereof means em-

bodying my invention is illustrated diagrammatically by way of example.

In the drawings

Fig. 1 is an elevation showing the eccentric and the clutch members on the shaft of an eccentric press.

Fig. 2 is an end elevation of Fig. 1, viewed from the left and partly broken away so as to show sections in the axis of the keys and in the axis of the eccentric pin connecting them, and

Fig. 3 is a section on the line 3—3 in Fig. 2, drawn to a larger scale.

Referring now to the drawings *a* is a journal on the shaft of an eccentric press, *b* is the eccentric which is free to rotate about the journal *a*, *c* are teeth at one end of the eccentric, *e* is the mating clutch member, and *c'* are teeth on the end of the second member which are adapted to mesh with the teeth *c* of the eccentric *b*. *d* is an extension of the shaft having two parallel faces as will appear from Fig. 2, on which the member *e* is fitted to slide but to partake in the rotation of the shaft *a*. Instead of being secured on a block having parallel faces, as shown, the member *e* might be held against rotation on a cylindrical part of the shaft by means of splines or the like. It will be understood that when the teeth *c*, *c'* are in mesh, the rotation of the shaft is transmitted to the eccentric *b*.

f and *f'* are keys which are fitted to rotate in radial co-axial bores of the member *e* at opposite sides of the flat faces by which the member is held against rotation. *r* is a pin arranged eccentrically with respect to the two keys *f*, *f'* in a bore *g* of the block *d* in which the pin *r* is free to rotate about the axis of the two keys *f*, *f'*. *t* are sleeves which are fitted at the ends of the bore *g* and provided with slots *q* which fit the pin *r* closely in the axial direction of the system but permit it to move in the sleeves, at right angles to this direction. *s* is a slot in one of the keys, in the present instance, the key *f*, for the insertion of a screw driver or the like, and *u* is a set screw engaging the key *f'*.

If it is desired to vary the relative position of the member *e* and the eccentric *b*, the

screw u is unscrewed, a suitable tool is inserted in the slot of the key f and the keys f, f' are rotated together, the rotation of the key f being transmitted to the opposite key f' through the medium of the pin r which is free to move in the sleeves t at right angles to the axis of the system, but is positively connected with the sleeves in axial direction so that it displaces the member e axially and moves its teeth c' out of mesh with the teeth c of the eccentric b . The eccentric is now adjusted, the key f is rotated in opposite direction so as to return the teeth c, c' into meshing relation, and the screw u is reset.

I wish it to be understood that I do not desire to be limited to the exact details of construction shown and described, for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:

1. Means for coupling a shaft or journal having a transverse hole with a member surrounding same having clutching means on said member, comprising a mating clutch member having a radial bore held against rotation with respect to said shaft but adapted to be displaced axially thereon, a pair of keys fitted to rotate in the opposite ends of said radial bore in said mating member, an eccentric pin extending freely through said hole in said shaft or journal from one key to the other, and a guide in said hole which is engaged positively by said eccentric pin in the direction of the axis of said shaft or journal but is provided with a clearance for said pin at right angles to said shaft.

2. Means for coupling a shaft or journal with a member surrounding same having clutching means on said member, and comprising an extension on said shaft having a transverse bore, a mating clutch member having a radial bore, non-rotatably but slidably mounted on said extension, a pair of keys fitted to rotate in the opposite ends of said radial bore in said mating member, an eccentric pin extending freely through said hole in said extension from one key to the other, and a guide in said hole which is engaged positively by said eccentric pin in the direction of the axis of said shaft or journal but is provided with a clearance for said pin at right angles to said shaft.

In testimony whereof I affix my signature.
MAX LUBICH.
